REVERSING VALVE FOR HYDRAULIC RECIPROCATING MOTOR

Karel Lodewijk Rethmeier, Delft, Netherlands, assignor to Shell Oil Company, a corporation of Delaware

Filed Mar. 24, 1958, Ser. No. 723,586

Claims priority, application Netherlands Mar. 26, 1957

1 Claim. (Cl. 121—46.5)

The invention relates to a hydraulic reciprocating motor in which the spaces on both sides of the motor piston are alternately connected to the supply and exhaust of a hydraulic medium by means of a slide valve.

It has been found that reversing the direction of movement of the piston is attended by rapid changes in pressure in the spaces on either side of the piston, these changes in pressure being shown by violent impacts against the cylinder covers and the piston and the parts connected therewith.

The object of the invention is to overcome this drawback.

To this end, according to the invention, one or more throttling passages are arranged in each valve face of the slide valve and/or in the part of the slide face working in conjunction therewith, the length of each throttling passage being at least equal to the width of the valve face, measured in the direction of travel of the slide valve.

As a result of the above arrangement, when the slide valve is reversed, the supply pressure prevailing in one cylinder space gradually passes over into the exhaust pressure, whereas the exhaust pressure prevailing in the other cylinder space is gradually converted into the supply pressure. Consequently, when the direction of movement of the piston is reversed, there are no sudden changes in pressure in the two cylinder spaces, as shown by violent impacts against the piston and the parts connected therewith, and against the cylinder covers.

The throttling passages are preferably formed by grooves arranged in the slide face in such a way that each cylinder port leads into a groove or set of grooves, substantially in the middle thereof.

In order to prevent unnecessary leakage losses through the throttling passages it is preferable to choose a width of each slide valve face working in conjunction with a cylinder port and increased by its stroke, which is larger than the distance between the ends of the groove(s) arranged in the slide face near this cylinder port; the width of the valve face and the said distance are measured in the direction in which the slide valve face concerned moves over the slide face.

Prior attempts have been made to reduce the rate at which the hydraulic medium is supplied to or withdrawn from the cylinder space when the slide valve is reversed by throttling the supply or exhaust by means of narrower grooves or channels arranged in the slide valve. By the above means the impacts are somewhat deadened, but they are not eliminated, since owing to the slight compressibility of the hydraulic medium, even the supply or discharge of an extremely small quantity of hydraulic medium to or from the closed cylinder spaces will result in a rapid rise or fall in pressure and an impact will consequently occur.

The way in which the occurrence of impacts in a hydraulic motor is prevented, according to the invention, will be more fully understood from the following detailed description and by reference to the accompanying drawing.

2

Figure 1 is a schematic diagram showing an elevation in section of hydraulic reciprocating motor valve mechanism and associated parts.

Figures 2, 3 and 4 are schematic diagrams showing the valve mechanism of Figure 1 at various positions of the slide valve.

Figures 1a, 2a, 3a, and 4a are pressure diagrams showing pressure conditions pertaining at the positions of the slide valve in Figures 1, 2, 3, and 4, respectively, with 10 configurations of the valve shown.

Figure 5 is an elevation in section of an alternate form of valve mechanism with the slide valve in one extreme position of travel.

Figure 6 is an elevation in section of the valve mechanism of Figure 5 showing the slide valve in an intermediate position.

The hydraulic reciprocating motor parts shown in Figure 1 comprises a cylinder 1 divided into two cylinder spaces A and B by a piston 2, which is connected to an 20 apparatus (not shown) by means of a piston rod 3.

Conduits or channels 4 and 5 connect the cylinder spaces A and B to the cylinder ports 7 and 8, respectively, which lead into the slide face 6. Moreover, a supply port 9 for the hydraulic medium also leads into 25 the slide face, which supply port is connected at the other end to a space (not shown) from where hydraulic medium is supplied under high pressure P_1 .

The slide valve 10 rests with the valve faces 11 and 12 on the slide face 6, which two valve faces are provided with grooves 13 and 14, respectively. These grooves connect the space 15 between the valve faces 11 and 12 to the part 16 of the slide valve chest lying outside the slide valve and connected by means of a conduit (not shown) to a space in which low pressure P_2 prevails.

35 In Figure 1 the slide valve 10 is in the middle position, i.e., it is placed symmetrically in relation to the cylinder ports 7 and 8. Since a pressure P_1 prevails in the space 15 between the valve faces 11 and 12 of the slide valve, which space is connected to the supply line 9, and a pressure P_2 , smaller than P_1 , prevails in the space 16 which is connected to the exhaust line, a leakage current will flow through the two throttling passages 13 and 14. The pressure drop caused by this leakage current is shown graphically in Figure 1a. This diagram and the symmetrical

40 position of the slide valve in relation to the cylinder ports show that when the slide valve is in the position shown in Figure 1, the pressure P_A in the cylinder space A is equal to the pressure P_B in the cylinder space B. For the sake of simplicity, the effect on the pressure drop of the reduction of resistance in the throttling passages at the cylinder ports has been ignored in the pressure diagram in Figure 1a and in the other pressure diagrams of the drawing.

45 In Figure 2, the slide valve 10 is in one of its extreme positions. The cylinder port 7 leading to the cylinder space A, is then fully opened and, if the pressure losses resulting from the flow of the medium through the ports are ignored, the pressure P_A prevailing in this space A will be equal to the discharge pressure P_2 . The cylinder port 8 leading to the cylinder space B is also fully opened,

50 and as this port is in communication with the supply port 9 via the space 15, the pressure P_B prevailing in the cylinder space B is equal to the supply pressure P_1 , if the pressure losses resulting from the flow of the medium through the passages are ignored. The pressure drop in the throttling passages 13 and 14 is shown graphically.

55 As a result of the difference in pressure prevailing over the piston, the latter moves in the cylinder. At the end of its stroke the direction of motion should be reversed, this being effected by reversing the slide valve 10 from its extreme position shown in Figure 2 to the opposite extreme position illustrated in Figure 4 in which the two

cylinder ports 7 and 8 are again fully opened, but in which position the cylinder port 7 is now connected to the space 15, so that the supply pressure P_1 prevails in the space A, and the cylinder port 8 is connected to the exhaust space 16, so that the discharge pressure P_2 prevails in the space B.

On account of the presence of the throttling passages 13 and 14, which during the reversal of the slide valve move across the cylinder ports 7 and 8, respectively, the pressure in the cylinder spaces A and B changes gradually. Figure 3, in which the slide valve 10 is shown in an intermediate position, shows that during the movement of the slide valve in the direction shown by the arrow, the cylinder ports 7 and 8 are successively connected to adjacent points of the throttling passages 13 and 14, respectively, so that during the sliding movement the pressure in cylinder port 7 gradually increases from P_2 to P_1 , whereas the pressure in the cylinder port 8 gradually decreases from P_1 to P_2 . As a result of the slight compressibility of the hydraulic medium, only a small quantity of medium will flow respectively into and out of the cylinder spaces A and B during these changes in pressure, so that the changes in pressure in the cylinder spaces A and B respectively may be considered equal to the changes in pressure occurring in the cylinder ports 7 and 8. Consequently, as in these cylinder spaces too the pressures change uniformly, no impacts will occur in the cylinder spaces during the reversal of the slide valve. The pressure drop over the lengths of the throttling passages 13 and 14 is somewhat affected by the medium flowing into and out of the cylinder ports 7 and 8 respectively, during the sliding movement; however, the pressure drop remains continuous, so that the shock-free reversal of the direction of motion of the piston is not affected by it. During the reversal of the slide valve from the position illustrated in Figure 4 the pressure in the cylinder spaces changes in the opposite direction.

In the same way as shown in Figures 2-4, the direction of motion of the piston can be reversed in a shock-free way by means of a device in which the throttling passages are formed by grooves arranged in the slide face 6. In another further embodiment the throttling passages may be formed by grooves arranged in the valve faces of the slide valve 10, which grooves work in conjunction with the grooves arranged in the slide face 6.

The application of the invention is not limited to any one type of slide valve; the slide valve may be one with either internal or external admission, it may contain either a reciprocating or a turning movement and have flat or cylindrical valve faces.

In Figures 5 and 6 a device is illustrated according to the invention in which the throttling passages are arranged in such a way that there will be no leakage currents through these throttling passages if the slide valve is put in one of its extreme positions, which results in a greater hydraulic efficiency of the motor.

Figure 5 shows a slide valve case 17 in which a cylindrical slide valve 18 can be moved to and fro by means of a slide valve spindle 19. The throttling passages are formed by grooves 23 and 24 arranged in the slide face 20 at the cylinder ports 21 and 22. Between the cylinder ports 21 and 22 a supply port 25 is arranged for supplying the medium under high pressure P_1 , which supply port 25 is always in communication with the space 28 arranged between the valve faces 26 and 27 of the slide valve 18. The hydraulic medium is discharged through the spaces 29 lying outside the slide valve, which spaces are connected to a space (not shown) in which a low pressure P_2 prevails.

In Figure 5 the slide valve 18 is in one of its extreme

positions in which the left-hand ends of the grooves 23 and 24 are closed. The pressure in the cylinder port 21, which is in communication with the cylinder space A, is then equal to the supply pressure P_1 , whereas the pressure in the cylinder port 22, which is in communication with the cylinder space B, is equal to the discharge pressure P_2 . As the grooves 23 and 24 are closed at one end, no leakage current flows through the throttling passages formed by these grooves when the slide valve is in its extreme position as shown in the drawing.

If, however, the slide valve 18 is moved to the right in order to reverse the direction of motion of the piston, both throttling passages are opened (see Figure 6) and as a result of the leakage current flowing through these throttling passages there will be a gradual pressure drop in the passages. A part of the leakage current through the throttling passage 24 is supplied via the cylinder port 22 to the cylinder space B adjacent to this port 22, as a result of which the pressure in this cylinder space gradually increases from P_2 to P_1 during the displacement of the slide valve 18, while sufficient hydraulic medium is supplied through the cylinder port 21 from the cylinder space A to the leakage current flowing through the throttling passage 23 for the pressure in this cylinder space to gradually decrease from P_1 to P_2 during the displacement of the slide valve 18.

Immediately before the slide valve has reached its opposite extreme position the change in pressure in the cylinder spaces is completed. In this second extreme position of the slide valve the other ends of the throttling passages 23 and 24 are closed by the valve faces 26 and 27 of the slide valve, so that during the displacement of the piston there is no leakage current through the throttling passages. During the reversal of the slide valve from this extreme position, the pressure in the cylinder spaces changes in the opposite direction.

The throttling passages in the extreme position of the slide valve as shown in Figure 5 is closed by choosing a width of each slide valve face working in conjunction with a cylinder port and increased by its stroke which is larger than the distance between the ends of the groove arranged in the slide face near this cylinder port; this width is to be measured in the direction in which the slide valve face moves over the slide face.

I claim as my invention:

In a hydraulic reciprocating piston motor, a reciprocating valve operating in the extreme positions of the motor piston, a casing having a slide face and valve ports communicating with the slide face through which hydraulic fluid may flow to actuate said motor piston, said reciprocating valve having valve faces disposed in sliding contact with said slide face throughout the entire length of travel of the reciprocating valve, said valve faces being wider than said valve ports and being movable over said valve ports, and throttling channels between said valve faces and said slide face, said throttling channels each having an effective length at least equal to the width of its valve face and being located so as to intersect a valve port during movement of said reciprocating valve.
